UNITED STATES PATENT OFFICE.

CHARLES A. TUCKER, OF BROOKLYN, NEW YORK.

DESIGN FOR A COLLAR-BUTTON.

SPECIFICATION forming part of Design No. 17,477, dated July 19, 1887.

Application filed May 16, 1887. Serial No. 238,429. Term of patent 31 years.

To all whom it may concern:

Be it known that I, CHARLES A. TUCKER, of Brooklyn, in the county of Kings and State of New York, have invented and produced a new and original Design for a Collar-Button, 5 of which the following is a full, clear, and exact description.

Reference is to be had to the accompanying drawings, forming a part of this specification, 10 in which similar letters of reference indicate corresponding parts in all the figures.

Figure 1 is a view of my newly-designed collar-button as seen from its top or head side. Fig. 2 is a side view of the same, and Fig. 3 15 is an upper end view thereof.

The distinguishing feature of this design is the peculiar configuration of the top or head of the button or stud.

A is the back of the button, which may be 20 of the usual flat circular shape, and B its shank, which may be of the usual flat wedge shape, as seen by looking at the button from above or below; or said back and shank may be of any other desired contour.

25 C is the elongated top or head of the button. This top or head has a marginal outline as

viewed from its face side d, of straight tapering form on both of its opposite side edges, as marked *a a* in Fig. 1, and said edges are slightly rounded and joined by convex outlines *b c* at their opposite ends. In side view or profile only the face d of said head or top is of tapering form and its back or opposite side, e, of straight outline and of flat configuration transversely, while the face side d is 30 of convex form transversely, with its opposite ends *f g* of semi-globular shape, all as shown in Figs. 1, 2, and 3 of the drawings, and the whole resembling the section of a pear divided longitudinally through its middle. 40

I claim—

The design for a collar-button herein shown and described, the same consisting of a collar-button having its top or head of a tapering figure on the opposite side edges of its front 45 and down or along its face, with a straight or flat back, and of convex form transversely on its face, with its ends of semi-globular shape. 45

CHARLES A. TUCKER.
